2,506,644

COAXIAL ELECTRON DISCHARGE DEVICE

Harwick Johnson, Princeton, N. J., assignor to
Radio Corporation of America, a corporation of
Delaware

Application December 18, 1947, Serial No. 792,469

15 Claims. (Cl. 315—39)

1

This invention relates generally to electron discharge devices and more particularly to an improved diode for generating noise currents.

A diode provides a convenient known noise source for use in determining the noise factor of radio circuits and components, particularly receivers. As a result of the shot noise currents therein due to the random transits of the individual electrons comprising the plate current, the diode may be considered a signal generator which furnishes a signal including all frequencies simultaneously throughout a large part of the frequency spectrum. If the diode is operated with temperature-limited emission from its filament, the noise current squared is accurately calculable.

For satisfactory use in measurement work, the noise diode must not disturb the circuit to which it is added, or any impedance added to the circuit by the diode must be capable of being incorporated in the circuit in a non-harmful manner. To satisfy these conditions at ultra high frequencies, the use of a diode in the form of a section of coaxial line has been suggested. Such a diode could be inserted into ultra high frequency coaxial line circuits without affecting the circuits.

In a copending application of Herbert A. Finke, Serial No. 724,208, filed January 24, 1947, entitled Coaxial electron discharge devices, now Patent No. 2,463,368, dated March 1, 1949, and assigned to the same assignee as the present application, there is disclosed a noise diode tube consisting of a section of 50 ohm coaxial transmission line wherein the outer cylindrical element of the coaxial pair serves as the anode and the inner element provides the cathode of the diode. The inner element is divided centrally into two portions separated by a mica insulating washer, and a cathode filament is mounted on and electrically connected to the adjacent ends of said portions, bridging the mica insulator. One of said portions is made hollow and the other portion is provided with an extension through the hollow portion, to provide for energizing the filament from one end of the tube. A vacuum envelope is provided by means of the anode and insulating sealing rings between the ends of the coaxial pair elements and between said hollow portion and said extension.

In the course of my work with the noise diode of said Finke application it became apparent that this construction did not simulate a 50 ohm coaxial line as well as was desirable and, in fact, could not be used as a known noise source over much of the ultra high frequency band. This was found to be due to the impedance discon-

2

tinuity produced by the break between the two portions of the inner conductor of the diode. The faces of the inner conductor portions bearing on the mica washer form a condenser which is intended to bypass the R. F. currents and provide continuity for the inner conductor. In addition, the break is shunted by the filament wire which tends to provide continuity at lower frequencies where the bypass capacity may not be effective. However, the bypass capacity and the filament inductance form a parallel L-C circuit in series with the inner conductor portions which at resonance introduces a very high series impedance at this point. This causes a very large reflection in a 50 ohm line connected as a continuation of the coaxial pair. This is evidenced experimentally by a high standing wave ratio measured in the neighborhood of 1750 megacycles.

In addition to this effect, the filament leads form a second coaxial line B, which may be considered to be effectively in series with the inner conductor of main pair A, but shunted by the filament and the bypass capacity. Thus some unknown impedance is present, at the break in pair A, due to the coaxial pair B, which impedance depends on the length of B, the termination of B, the frequency, and the effectiveness of the shunting capacity and filament. It was determined experimentally that the bypassing effect of the capacity was not adequate to prevent a reflection from being introduced into pair A from pair B at this point. In fact, the reflection in A even varied with the manner of making connections to coaxial pair B, making it extremely difficult to bring out the filament leads to the filament supply without introducing a reflection into pair A.

The instant invention is an improvement upon the noise diode disclosed in said copending Finke application.

A particular object of this invention is to provide a thermionic source of noise voltages having a fixed characteristic impedance which is substantially independent of frequency.

A further object is to improve the impedance characteristics of the Finke noise diode while retaining the advantageous features thereof.

A particular feature of the invention is the elimination of the break in the inner conductor of the Finke noise diode.

Other objects will be apparent from the following description of the invention pointed out in particularity in the appended claims and taken

in connection with the accompanying drawing, in which:

Fig. 1 is a central longitudinal sectional view of a two-element vacuum tube constructed in accordance with a preferred embodiment of the invention;

Fig. 2 is a transverse sectional view taken along the line II—II of Fig. 1;

Fig. 3 is a similar view taken along the line III—III of Fig. 1;

Fig. 4 is a fragmentary plan view taken in the direction IV—IV of Fig. 1;

Fig. 5 is a central longitudinal view of a modified construction; and

Fig. 6 is a graph showing the improved relation between the voltage standing wave ratio and frequency in a 50 ohm line when my diode is inserted in the line ahead of a 50 ohm lossy line, as compared with the Finke diode and a 50 ohm lossy line.

Referring to Fig. 1, the tube generally comprises a section A of coaxial transmission line having a diametric ratio which will give a characteristic impedance generally encountered in the component elements to which the tube will be connected, for example, 50 ohms. The section A comprises a hollow cylindrical outer conductor 1 and a cylindrical inner conductor 2 which carries the cathode filament 3. In order to maintain the coaxial arrangement, insulating rings 4 of glass are sealed between the ends of the outer conductor 1 and the inner conductor 2. Suitable means, such as the tube 5, is provided for evacuating the space within the tube.

The tube structure just described is generally the same as that of the Finke tube. However, the structure of my inner conductor 2 is quite different. The conductor 2 consists of two telescoping rods 7 and 8, each of which is undercut, as shown at 9, at each of the rings 4 to compensate partly for the change in characteristic impedance at these points due to the presence of the glass. Rod 7 is hollow to accommodate an elongated rod terminal 10 supported coaxially therein by an insulating glass bead 11 and a seal 11'. The inner end of terminal 10 has a lateral lug 12 which extends outwardly through the enlarged part 13 of a key-hole slot 14 formed in the wall of the inner end of hollow rod 7. An S-shaped filament support 15 is secured to rod 7 adjacent the lateral lug 12. The ends of the filament loop 3 are attached to the lug 12 and support 15.

The rod 8 is provided with a reduced diameter inner portion 16 which fits snugly within a counterbore 17 of rod 7, as shown in Figs. 1, 3 and 4, thereby providing a low resistance connection therebetween.

In order to provide a large bypass capacitance between coaxial elements 7 and 10, the reduced portion 16 of rod 8 is formed with a slot 18 in which is disposed a condenser plate 19 which is welded to lug 12 and insulated from rod 8 by two dielectric strips 20 of mica of greater width than the condenser plate 19. The outer edges of the mica strips are accommodated in the slot 14 and a diametrically opposite slot 21 formed in the counterbored portion 17 of rod 7.

The assembly of the tube is preferably carried out as follows. First, the condenser plate 19 and terminal 10 are aligned and the offset portion 19' is spot welded to the side of the lug 12. The plate 19 is then inserted with the two mica strips 20 into the slot 18 of rod 8, after which the tubular rod 7 is slipped over the terminal 10

and reduced portion 16 of rod 8, the slot 14 providing sufficient clearance for passage of the lug 12 and associated elements. The outer end of rod 7 is then sealed to the terminal by means of the glass seal 11' with the lug 12 centered within the opening 13. The support 15 is spot welded to rod 7 and the filament loop is spot welded in place. Now, the assembled inner conductor unit is inserted within the outer conductor 1, to which the evacuating tube 5 has been attached, and the glass rings 4 are sealed in place to complete the vacuum envelope.

In the operation of the tube for determining the noise factor of a receiver or other electronic circuit component, the tube is coupled to said component by a suitable section of coaxial transmission line. A source of anode potential is connected between the outer conductor 1 and inner conductor 2 and a variable source of heating current for the filament 3 is connected between the hollow rod 7 and rod 10, at the end of the tube opposite the coaxial connection with said component. The method of measurement of the noise factor is the same as that described in the above-mentioned Finke application. With an anode voltage of 300 volts the filament emission of the tube is temperature-limited up to about 100 milliamperes. This emission enables the measurement of noise factors up to about 20 decibels at low frequencies. Transit-time effects reduce this to about 17 decibels near the upper end of the ultra-high frequency band. A complete analysis of the design and operating characteristics of the diode is embodied in a paper entitled "A coaxial-line diode noise source for U. H. F.," presented by me at the 1947 I. R. E. National Convention on March 3, 1947, and published in RCA Review, March 1947.

It is seen that in my improved structure each of the inner and outer conductors, and hence, the coaxial pair A, is conductively continuous throughout the tube with no gap in either conductor where a series impedance can exist. This eliminates the reflections due to resonance of the series L-C circuit formed by the filament inductance and the bypass capacity in the Finke diode. Reflections which may arise from the magnetic coupling of the filament to the inter-electrode space of coaxial pair A are minimized by placing the filament substantially in a radial plane as shown in Fig. 1.

The coupling of coaxial pair B to coaxial pair A is principally effected through the magnetic coupling of the filament loop which is minimized as stated above. In my improved tube the bypass capacity which shunts coaxial pair B has a much larger capacitance than that available in the Finke tube, and hence, provides a much more effective bypass.

While it is preferred to construct the diode with the bypass condenser it has been found that the condenser can be omitted without seriously affecting the performance of the tube.

In the preferred embodiment of Figs. 1-4 the inner conductor of the diode is made up of two closely-fitting telescoped parts, to facilitate assembly of the parts. However, in the modification shown in Fig. 5 the inner conductor is a one piece rod 2'. One end 7' of the rod 2' is hollowed out to receive the filament terminal 10'. A longitudinal slot 14' is cut in the solid end 8' of the rod of sufficient width and length to permit insertion of the terminal 10' in the direction of the dashed lines shown. An enlarged opening 13' is provided adjacent the intersection of the

slot 14' with the hollow part 7' to receive the lateral lug 12' of the terminal in spaced relationship. After the terminal 10' has been inserted through the slot 14', a glass sleeve 11' is inserted from the outer end of the part 7' and sealed between the latter and the terminal 10'.

The effectiveness of my improved tube compared to that of the Finke tube over a wide frequency range is demonstrated in part by lines *b* and *a*, respectively, of Fig. 6. For comparison, the standing wave ratio for a 50 ohm lossy line is shown at *c*.

Although my improved tube has been described in connection with its use as a noise diode for a certain receiver test and measurement, it is evident that a device of this type may have various other applications wherever it is desirable to maintain a certain circuit impedance and have at the same time an electron discharge device in this circuit without disturbing the transmission characteristics thereof. It will also be evident that, instead of being limited to a two-element tube, other elements may be incorporated in my tube. Therefore, while I have indicated the preferred embodiments of my invention of which I am now aware and have also indicated only certain specific applications for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

I claim:

1. An inner conductor for an electron discharge device, comprising a hollow rod, a solid rod having a reduced diameter portion snugly fitting within one end of said hollow rod, the wall of said hollow rod being formed with an aperture adjacent the end of said reduced portion, an elongated terminal insulatedly supported within said hollow rod and having a lateral portion extending through said aperture, and a filament surrounding said hollow rod and supported by said lateral portion and said hollow rod.

2. An inner conductor in accordance with claim 1, including a condenser connected between said terminal and one of said rods.

3. An inner conductor in accordance with claim 2, wherein a slot is formed in said reduced portion, and said condenser comprises a flat plate disposed in said slot between two dielectric strips and conductively connected to said terminal.

4. An electron discharge device including a section coaxial transmission line consisting of a hollow cylindrical outer conductor and an inner cylindrical conductor, said outer conductor constituting an anode, one end of said inner conductor being formed with a hollow portion and a radial aperture at the inner end of the hollow portion, an elongated terminal supported in said hollow portion and aperture and insulated from said inner conductor, and a filamentary cathode surrounding said inner conductor and supported by said terminal and said inner conductor.

5. An electron discharge device in accordance with claim 4, including a condenser connected between said terminal and said inner conductor.

6. An electron discharge device in accordance

with claim 5, wherein said inner conductor is formed with a longitudinal slot adjacent said terminal, and said condenser comprises a flat plate disposed in said slot between two dielectric strips and conductively connected to said terminal.

7. An inner conductor for an electron discharge device, comprising a rod having a hollow portion extending from the approximate center thereof to one end, said hollow portion being formed at its inner end with a radial aperture, an elongated terminal supported in said hollow portion and said aperture and insulated from said rod, and a filament surrounding said rod and supported by said terminal and said rod.

8. An inner conductor in accordance with claim 7, including a condenser connected between said terminal and said rod.

9. An inner conductor in accordance with claim 8, wherein said rod is formed with a longitudinal slot adjacent said terminal, and said condenser comprises a flat plate disposed in said slot between two dielectric strips and conductively connected to said terminal.

10. An electron discharge device comprising a section of coaxial transmission line composed of a hollow cylindrical outer conductor, a cylindrical inner conductor extending through said outer conductor and insulating means supporting said inner conductor coaxially within said outer conductor, both of said conductors being conductively continuous throughout the length of said device, and thermionic cathode means supported by said inner conductor in the space between said conductors, said outer conductor being adapted to function as the anode element of said device upon thermionic emission of said cathode.

11. An electron discharge device in accordance with claim 10, wherein said insulating means provide hermetic sealing of said section at each end whereby the section may be evacuated.

12. An electron discharge device in accordance with claim 10, wherein said thermionic cathode means surrounds said inner conductor.

13. An electron discharge device in accordance with claim 1, wherein the wall of said hollow rod is formed with a longitudinal slot extending from said aperture to the end of the rod, to permit assembly of said lateral portion of said terminal within said aperture.

14. An electron discharge device according to claim 4, wherein said inner conductor is a one piece rod.

15. An electron discharge device according to claim 14, wherein said rod is formed with a longitudinal slot extending from said radial aperture toward the other end of said rod, to permit assembly of said terminal within said hollow portion and aperture.
